UNITED STATES PATENT OFFICE.

RALPH P. THOMPSON, OF SPRINGFIELD, ASSIGNOR TO C. W. PRICE, OF GREENFIELD, OHIO.

CASH-REGISTER.

SPECIFICATION forming part of Letters Patent No. 521,558, dated June 19, 1894.

Application filed March 18, 1893. Serial No. 466,602. (Model.)

To all whom it may concern:

Be it known that I, RALPH P. THOMPSON, a citizen of the United States, residing at Springfield, in the county of Clark and State 5 of Ohio, have invented certain new and useful Improvements in Cash-Registers, of which the following is a specification.

My invention relates to that class of cash registering devices in which a normally closed 10 cash receptacle is arranged in connection with registering devices to register the amounts placed in said receptacle.

The object of my invention is to provide means, the operation of which prevents the 15 locking of the cash receptacle until a registration has been effected by the operation of one or more of the registering devices. I attain these objects by the construction shown in the accompanying drawings, in which—

20 Figure 1 is a sectional elevation of a device embodying my invention. Fig. 2 is a similar elevation illustrating a modification. Fig. 3 is a detail, showing a further slight modification. Fig. 4 is a sectional elevation, 25 showing the drawer open and a key operated. Fig. 5 is an enlarged sectional view, illustrating the same parts as in Fig. 3, with the drawer open and the keys in their normal position.

30 Like parts are represented by similar letters of reference in the several views.

In the said drawings *a*, represent an outer casing.

35 *b*, is the cash receptacle, which is preferably in the form of a sliding drawer, adapted, when released, to be forced outwardly and thus opened by a spring *b'*. The drawer is locked in a closed position by a pivoted locking bar *c*, adapted to engage with a lug or 40 projection *c'*, on the drawer. This locking bar *c*, is adapted to be operated by a lever *d*, pivoted at *d'*, and having a handle *d''*, projecting through the casing; a projection *d''*, on said lever being adapted to contact with 45 a projection *c''*, on the locking bar to raise said bar out of contact with the lug or projection *c'*, when the handle *d''*, is operated. A series of operating levers *e*, preferably provided at one end with the ordinary indicating tablet *e'*, and at the opposite end with a numbered key *e''*, are also arranged within the

casing and preferably employed in connection with any of the well known cash registering devices, such, for instance, as illustrated at *g*, in Fig. 4 to cause the proper registration of the amounts deposited in the cash receptacle in a well known manner. The constructions thus described form no part of my invention and any of the well known devices now in use may be employed. In connection 55 with these devices I employ an intermediate device adapted to be operated by any one of the keys in the series; said intermediate device being adapted to prevent the locking of the drawer until one or more of the key levers are 60 depressed. This result is preferably accomplished by interfering with the operation of the locking device of the drawer. This is 65 preferably accomplished by providing a bar *f*, extending entirely across the series of keys 70 *e*. This bar may be supported by suitable arms *f'*, pivoted in the casing at *f''*, and provided with a downwardly projecting finger *f''*, adapted to engage with an upwardly projecting spur or finger *c''*, on the locking bar *c*, and thus hold the locking bar out of contact with 75 the drawer when the keys are all in the normal position and until it is released by the raising of the bar *f*, which can only be accomplished by the operation of a key. 80

In most of the cash registers now in use the amounts last registered are indicated by the elevated tablets which remain in this elevated position until the drawer is again opened or other keys operated, and it is to 85 this class of registers that the device illustrated in Fig. 1 is particularly adapted; the operating key or keys being adapted to hold the bar *f*, in the elevated position and out of contact with the locking bar during the time 90 the drawer remains closed. I have illustrated a similar method of accomplishing this result by providing a lug or projection *e''*, on each of the levers *e*, adapted to engage a similar lug or support *d''*, on the lock operating lever *d*. When a key is depressed the lug *e''* comes against the corresponding projection *d''*, which retains it in an elevated position until the handle *d''*, is operated to release the drawer, at which time the same 95 movement releases all the keys which are in an elevated position, thus bringing the bar

f, and the intermediate connected devices in position to retain the lock out of engagement with the drawer until a key is again depressed, so as to elevate the bar as before.

5 In that class of registering devices in which the keys are returned to their normal position by the closing of the drawer, a loose connection should be formed between the bar *f*, and the locking bar *c*, which will permit the 10 bar *f*, to return to its normal position while the locking bar is in its normal position. This may be accomplished as shown in Fig. 3 by placing a pivoted intermediate finger *f*⁴, between the projection *f*³, and the projection 15 *c*⁴; said finger being adapted to engage the locking bar as shown in Fig. 5 whenever the same is operated to release the drawer, and hold it so engaged until the finger is withdrawn therefrom by the elevation of the bar 20 *f*, which brings the projection *f*³, in contact with the finger *f*⁴, and thus releases the locking bar.

The finger *f*⁴, under ordinary conditions, is preferably operated by gravity, as shown in 25 Fig. 3, though if desired a spring may be attached thereto, as shown in Fig. 5, to return it to its normal position. The same is true of the levers *d*⁴. In Figs. 1 and 2 I have shown these constructed to return to their normal 30 position by gravity. In Fig. 4 springs are shown employed for effecting this result; but the operation is the same in either case, and it is my intention to employ either construction as may seem the best adapted to the circumstances under which the machine is to 35 operate.

In Fig. 2 I have shown a modification in which the projection *c*³, on the locking bar is dispensed with; the drawer in this case 40 being unlocked by the dropping of the bar *f*, whenever the keys are moved to their normal position, by operating the lever *d*; the weight of the bar *f*, being sufficient to elevate the locking bar *c*.

45 It is obvious that various modifications may be employed for carrying out my invention. I do not, therefore, limit myself to the exact constructions shown and described; but I claim broadly as my invention—

50 1. In a cash register, a normally locked cash receptacle, a series of operating keys, means for unlocking said receptacle independent of the operation of said keys, and means for preventing the relocking of said 55 cash receptacle until one or more of said keys have been operated, substantially as specified.

2. In a cash register, a normally closed cash drawer or receptacle and operating keys, controlling devices by the operation of which 60 the opening of said drawer or receptacle is

effected, and mechanism connected to said keys to prevent the return of said drawer or receptacle to its normal condition until a key has been operated, substantially as specified.

3. In a cash register, a cash receptacle, a 65 series of operating keys, and mechanism the operation of which effects the opening of said receptacle, a retaining device released by the operation of said mechanism and when so released prevents the locking of said cash receptacle in its closed position until said retaining device has been acted upon by the operation of a key, substantially as specified. 70

4. In a cash register, the combination with the registering keys and the cash drawer or 75 receptacle, as described, an intermediate engaging device adapted to be released by the unlocking of said drawer or receptacle so as to contact with the locking mechanism and prevent the re-locking of said drawer or receptacle, said engaging device being connected with said keys so as to be returned to its normal position by the depression of a key, substantially as specified. 80

5. In a cash register, the combination with 85 the cash drawer, of a catch for holding the drawer closed, a series of keys, a lever, and connections whereby the operation of one or more of said keys throws the catch into position to engage the drawer, and the operation 90 of said lever disengages the catch from the drawer, substantially as set forth.

6. In a cash register, the combination with a cash drawer, of a catch for holding the drawer closed, a series of keys, a connection 95 whereby the operation of one or more of said keys throws the catch into position to engage the drawer, means for disengaging the catch from the drawer, and means for preventing the catch from engaging the drawer again until one or more of said keys have been operated, substantially as set forth. 100

7. In a cash register, the combination with the cash drawer, of a catch for holding the drawer closed, a series of keys, a lever, and 105 connections whereby the operation of one or more of said keys throws the catch into position to engage the drawer, and the operation of said lever disengages the catch from the drawer, and means to prevent the catch, after 110 the operation of said lever, from engaging the drawer again until one or more of said keys have been operated, substantially as set forth.

In testimony whereof I have hereunto set my hand this 11th day of March, A. D. 1893. 115

RALPH P. THOMPSON.
